FIELD JACKET HOOD

Joseph De Grazia, Washington, D. C.

Application June 1, 1945, Serial No. 597,055

5 Claims. (Cl. 2—84)

(Granted under the act of March 3, 1883, as amended April 30, 1928; 370 O. G. 757)

1

The invention described herein, if patented, may be manufactured and used by or for the Government for governmental purposes, without the payment to me of any royalty thereon.

The invention concerns a winter head covering or hood designed for use of the armed forces and worn by both men and women, usually with the regulation field jacket of the armed forces.

It is an object of the invention to provide a warm head covering of the hood or helmet style which can be secured to the field jacket by means of the buttons provided thereon for the regular use of the jacket, that is, without the necessity of providing special buttons to secure the hood.

It is a further object of the invention to provide a wind resistant and water resistant head covering for the use of hunters, followers of winter sports and outdoor workers in general, which can be worn combined with any front closing coat or jacket having its buttons spaced properly with relation to the hood.

Further objects of the invention will appear from the description of the invention taken in connection with the accompanying drawing, in which:

Fig. 1 is a perspective view of a soldier wearing the field jacket and hood,

Fig. 2 is a side elevation of the folded hood or helmet,

Fig. 3 is a front elevation of the hood with the flaps extended,

Fig. 4 is a perspective view of a woman wearing the woman's field jacket and helmet,

Fig. 5 is a perspective view, partly broken away, of the hood illustrated in Figs. 1 to 3, in engagement with a shoulder strap button.

In the drawings A represents a helmet or hood constructed according to the present invention and B represents the standard field jacket of the Army. The field jacket comprises a body portion 10, having the conventional shoulder straps 11, provided with a button 31 and button-hole securing means for the end of the strap adjacent the shoulder. Two of the buttons closing the fly front of the jacket are shown at 12 and 13, and the collar 14 is shown raised with the throat tab 15 buttoned thereto at 16.

The hood comprises side sections 17, secured together by a median seam 18 and having facing members 19 and 20. The facing member 19 forms a hem for a drawstring 21 which emerges through eyelets 22 in the fabric of the hood. The drawstring is knotted or otherwise provided with

2

thickened portions at 23 to keep the ends from being drawn into the hem.

The lower or neck portion of the hood as shown in Fig. 1 has side flaps or extensions 24 and 25 which are adapted to be secured together under the chin of the wearer to complete the conventional helmet form. The closing of these flaps differs from the closing of previously known hood fronts in that it provides for securing the hood to the buttons of the wearer's coat, in this case the field jacket B. For this purpose the flaps 24 and 25 are provided with a single button 26 and buttonhole 27 placed at the upper part of the vertical fronts of the side flaps. These, in conjunction with the drawstring 21, which is adapted to draw the hood opening snugly around the face of the wearer, close the front of the hood or helmet.

In addition to this closing the hood A is provided with four buttonholes in the lower edge. The two buttonholes 28 and 29 at the lower end of the vertical fronts are adapted to be attached to the upper button 12 of the field jacket B. This fastening not only finishes closing the hood, but secures it firmly to the field jacket, thereby keeping it in place and forming a windproof joint with the jacket. The side buttonholes 30 are adapted to be secured to the shoulder buttons 31 of the shoulder straps 11, thus completing the attachment of the hood to the jacket.

The hood is made of any suitable material as wind resistant and water resistant cotton Oxford cloth, or it may be made of wool or any desired material.

Because of the left-over-right closing of the man's field jacket, the left flap 25 of the man's hood is made longer than the right flap 24, as shown in Fig. 1. Fig. 4 shows the right flap 24' of the woman's hood made longer than the left flap 25' to conform to the right-over-left closing of the woman's jacket. The relative lengths of the two flaps depends on the extent to which the coat fronts overlap, that is, on the width of the double-breasted overlap.

To attach the hood A to the field jacket B the shoulder straps 11 of the jacket are unbuttoned and buttonholes 30 of the hood A are buttoned on to the shoulder buttons. The shoulder straps are then rebuttoned over the hood. The turn up collar 14 is then raised and the throat tab 15 of the jacket is buttoned on to the collar buttons 16. The shorter flap of the hood is next buttoned over the upper exposed button 12 of the jacket, as shown in Figs. 1 and 4, and the longer flap is then buttoned on to the same button. The

wearer then inserts the button on the shorter flap of the hood in its buttonhole in the longer flap, adjusts the drawstring 21 and ties it. The hood is worn under the steel helmet if conditions require the wearing of the latter.

It will thus be seen that a hood has been provided which affords complete protection to the neck and ears of the wearer and which is secured to the field jacket or other coat by a wind-proof and rainproof connection. At the same time, no extra fastening means is required on the jacket for the attachment of the hood.

It will be noted that the hood can be secured to any military garment provided with shoulder loops buttoned at the free end, including a garment having a double-breasted buttoned front closing. It will be necessary only to have the upper closing button of the coat located at the proper level to match the buttonholes on the hood. The hood can also be worn with non-military coats, as the front anchoring means is effective even without the shoulder fastening.

Having thus described my invention, what I claim is:

1. A helmet comprising a head portion and a neck encircling portion having overlapping front flaps and having means adapted to be secured to a coat having shoulder straps, shoulder strap buttons, a fly front and closure means for said fly front including a top button, said first-named means comprising buttonholes at the shoulder point and at each side of the front of the neck encircling portion, said buttonholes at the front adapted to be brought into alignment with each other and with said top button for securing said buttonholes to said top button.

2. A helmet comprising head and neck portions, said neck portion being open at the front and having overlapping side flaps, one of said flaps being longer than the other and both being provided with buttonholes adapted to be brought into alignment with each other when said flaps are in neck-encircling position, whereby the flaps may both be secured to one of the upper buttons of a coat.

3. A helmet comprising head and neck portions, said neck portion being open at the front and having overlapping side flaps, one of said flaps being longer than the other and both being

5 provided with buttonholes adapted to be brought into alignment with each other when said flaps are in neck-encircling position for securing the flaps to one of the upper buttons of a coat, said flaps also having cooperating means to secure them together above the said buttonholes.

10 4. In combination, a jacket having a buttoned front closing and shoulder straps buttoned at the end adjacent the neck and a hood having a neck portion provided with front closing flaps, said flaps having buttonholes at their front edges, 15 said buttonholes being adapted to be brought into alignment with each other when said flaps are in neck-encircling position to engage one of the front buttons of the jacket, said neck portion also having buttonholes to engage the shoulder strap buttons of the jacket.

20 5. In combination, a coat having a buttoned front closing and a hood having a neck portion provided with overlapping front closing flaps, one 25 of said flaps being longer than the other and both being provided with buttonholes adapted to be brought into alignment with each other when said flaps are in neck-encircling position, whereby the flaps may both be secured to an upper 30 button of the coat.

JOSEPH DE GRAZIA.
